UNITED STATES PATENT OFFICE.

HENRY J. MEADER, OF UTICA, NEW YORK, ASSIGNOR TO THE FLINTKOTE COMPANY,
OF BOSTON, MASSACHUSETTS, A CORPORATION OF MASSACHUSETTS.

PAPER MACHINE.

Application filed October 30, 1919. Serial No. 334,458.

My invention relates to an improvement in paper machines and refers more particularly to cylinder machines in which the water is automatically drawn from the paper stock or pulp after the stock has been picked up from the vat by an endless wire mesh or screen which travels over a cylinder or drum before spreading stock into sheets.

Among its salient objects is to provide a machine in which the stock after being thoroughly mixed in a vat is drawn upon a mesh surfaced cylinder which is divided longitudinally into compartments; to provide a machine in which said cylinder is rotated past suction pipes arranged at one or both ends of the cylinder above the surface of the stock in the vat, having mouth-pieces or valve plates to register with the ends of the compartments, to complete the suction chambers; to provide a machine which draws the water from the paper stock that is spread upon the mesh surface of the cylinder by the use of suction pipes which draw the water from the compartments with the successive registering of the compartments with the mouth-pieces of said suction pipes; to provide a machine in which the drying process is materially shortened, and in general to provide a machine of the character referred to.

Reference may here be made by my Patent No. 923,870, issued June 8, 1909, wherein a wire mesh travels around and upon the cylinder and is carried over a series of drying rolls and suction boxes to couch rolls and thence to the presses. My present improvement consists in the construction of the cylinder used in conjunction with the above patent as explained above and is furthermore and more particularly described hereinafter.

In the drawings:—

Fig. 1 is a side elevation partly in section, of as much of the machine as is necessary to show the application of my invention thereto.

Fig. 2 is a front elevation of the cylinder with parts broken away, to show the form of construction whereby the suction may be applied to the ends of the cylinder.

In Fig. 1 of said drawings, 1 is a vat for containing the stock, 2 is a cylinder mounted in said vat on a shaft 3. The vat has an inlet port 4 for admission of the stock and it

is also provided with a false bottom 5 which causes the stock entering through port 4 to pass down into the bottom of the vat under the cylinder and below the false bottom in the direction indicated by arrows as seen in Fig. 1. The stock is caused to become thoroughly commingled in the vat and is in a perfectly homogeneous condition throughout where it comes in contact with the mesh thus producing an even adhesion of paper to the mesh. Around the cylinder and adapted to have continuous motion is a wire mesh 6, a portion of which is at all times submerged in the vat. The mesh after leaving the cylinder passes over table rolls 7 and suction boxes 7^a and thence to the couch rolls and thence back over rolls 9 which impart tension and change direction as may be desired to the cylinder, the travel being in the direction indicated by arrows in Fig. 1. A deckle 10 of the usual construction is mounted wholly within the vat. This prevents the deckle from becoming injured by any means outside of the vat and a shower of water (not shown) keeps it clean and free from dirt.

In Fig. 2, is shown in more detail the construction of the cylinder. It has a series of partitions 11 radiating from the shaft 3 and dividing cylinder longitudinally into pockets or compartments 12. These compartments are air tight with exception of that part of each which is the cylinder facing or mesh and the ends. As the cylinder rotates these compartments, one or more at a time, are capped by the stationary valve plates 13 and come into registration with said valve-plate in such a manner that the ends of said compartments are closed air tight except for mesh cylinder surface and the pipes or outlets 14 in which is formed a suction or partial vacuum. The suction through pipes 14 and a similar outlet 15 on the opposite side, materially assists in drawing the water from the stock which has adhered to the outside of the cylinder facing, thus helping to dry the sheet formed on the mesh. Outside of the vat is a water reservoir 16 and leading from a cylindrical screen thereto is a port 17 in the wall of the vat 1, and leading from the water reservoir 16 is the discharge 18. It is understood that this arrangement may be so constructed that it in no way interferes with the forming of a sheet on said mesh when there is no suction

applied. In such a case, the cylinder may be used in the ordinary manner, although without the use of the suction-cylinder, a very much smaller quantity of paper can be produced with the same number of drying rollers. A more expensive operation is necessary to dry the sheet if the water is only partially removed, and this mode of removing a greater part of the water materially accelerates the production of the paper.

Although in the specification I have explained the suction drying device in connection with my paper machine, it is not my intention to limit its use to this particular type of machine, for it can readily be seen that this suction arrangement may be adapted to any type of cylinder machine and attain like results.

I claim as my invention:

- 20 1. In a paper machine, the combination with a vat, and an inlet port for introducing paper stock, of a rotatable cylinder having a series of partitioned walls mounted therein, an endless wire mesh adapted to travel around said cylinder and means for drawing water from the cylinder compartments above the surface of the paper stock in the vat prior to its leaving the cylinder.
- 25 2. In a paper machine, the combination with a vat having a false bottom and inlet port for introducing paper stock, of a rotatable cylinder longitudinally partitioned

into compartments, an endless wire mesh adapted to travel around said cylinder and a suction pipe and valve plate arranged above the surface of the paper stock in the vat to form suction chambers of the cylinder compartments and draw water from same.

3. In a paper machine, the combination with a vat having a false bottom and inlet port for introducing paper stock, of a rotatable cylinder mounted therein having a series of partitioned walls radiating from the center of the cylinder and running longitudinally of the cylinder, an endless wire mesh adapted to travel around said cylinder and suction pipes with valve plates arranged to cover the ends of cylinder compartments, thereby completing suction chambers for drawing water from said compartments.

4. In cylinder paper machines, the combination with a rotating cylinder having a sheet forming screen for picking up the paper stock passing thereover and, longitudinally partitioned to form compartments, of a suction means consisting of suction pipes with valve plate mouth pieces adapted to register with the open ends of the cylinder compartments to form a partial vacuum in suction chambers for drawing the water from the paper stock.

HENRY J. MEADER.
